UNITED STATES PATENT OFFICE.

WILLIAM C. O'BRIEN, OF BALTIMORE, MARYLAND.

METHOD OF ATTACHING FERRULES TO UMBRELLA-CASES.

1,113,574.

Specification of Letters Patent.

Patented Oct. 13, 1914.

Application filed November 23, 1911. Serial No. 662,000.

To all whom it may concern:

Be it known that I, WILLIAM C. O'BRIEN, a citizen of the United States, residing at Baltimore, in the State of Maryland, have 5 invented certain new and useful Improvements in Methods of Attaching Furrules to Umbrella-Cases, of which the following is a specification.

My invention relates to a method of attaching ferrules to tubular fabrics, and has 10 special utility when applied to the attaching of such ferrules to the ends of umbrella cases. As is well known, the ordinary method now in use for attaching these ferrules is simply to bind the fabric to them 15 by means of a piece of flexible wire or thread, the operation being performed entirely by hand. This method is tedious and expensive, and is open to the further objection 20 that the results are not satisfactory, since it has been found in practice that the fastening is not secure, and that the ferrules frequently become detached and lost.

The object of the present invention is, 25 therefore, to provide an improved method for attaching the ferrules, which method is carried out by means of a machine, whereby much more rapid and economical operation is obtained, and a much neater and stronger 30 fastening produced.

In order that my improved method, and machine for carrying the same into effect, may be clearly understood, reference is had 35 to the accompanying drawings, forming part

Figure 1 is a perspective view of the complete machine; Fig. 2 is a fragmentary side elevation of part of the machine showing the stripping device, parts being shown in 40 section; Fig. 3 is a side elevation of one of the ferrules, this view also illustrating, in section, a ring which I employ as a fastening means; Fig. 4 is a view similar to Fig. 3, showing the appearance of the ferrule 45 and ring after having been operated upon by the machine; Figs. 5, 6, 7 and 8 are detail sectional views illustrating the successive steps employed in assembling and uniting the parts, these views also showing 50 my improved dies; Figs. 9 and 10 are fragmentary sectional elevations showing my improved stripping device and method of using the same.

Referring to the drawings in detail and 55 more particularly to Fig. 3, B represents a ferrule of the usual type such as is ordi-

narily employed to form the tip of umbrella cases. This ferrule comprises a tapering sheet metal ring or shell, in the larger portion of which is formed an exterior annular groove or depression b, the shoulders c and d at the margins of the groove being of slightly different diameters, the shoulder c being the smaller. The groove, as well as its marginal shoulders are spaced from the 60 ends of the ferrule, but being closer to one 65 end than the other.

In forming my improved fastening I make use of a ring C which, as clearly shown 70 in Fig. 3, is capable of passing over the shoulder c but cannot pass over the shoulder d. This enables the ring to be slipped over the ferrule from the small end thereof and the shoulder d then acts as a stop to position the ring adjacent the groove b.

In carrying out my improved method I employ a machine embodying as its essential features a pair of die members 10 and 14, which are shown in Figs. 5 to 8, inclusive. By reference to these figures, it will be seen 80 that the lower member 14 is provided at its upper end with a matrix 13 the upper part of which conforms to the shape of the lower part of the ferrule B. The upper die member 10 is in the nature of a plunger, and is 85 provided with a nose 12 of slightly smaller diameter than the matrix 13. Between the nose 12 and body 10 of this die member there is provided an enlarged portion 10^y having curved or rounded sides, as clearly shown in 90 Figs. 7 and 8, and separated from the body 10 of the die member by means of an annular shoulder 10^x. The size of the enlarged portion 10^y is such that it can be forced into 95 the large end of the ferrule.

The method of attaching a ferrule to an umbrella case will now be described, the case itself being of any desired construction, and being indicated in its entirety by the reference character A.

The case having previously been turned wrong side out is first slipped over the die member 14, as shown in Fig. 5, and a ring C is then threaded over the end a of the case. A ferrule B is then inserted in the end of 105 the case the smaller end down, as shown in Fig. 6, and the ring C adjusted until it occupies a position adjacent the groove in the ferrule. The parts thus assembled are then lowered until the ferrule seats snugly 110 in the matrix, as shown in Fig. 7. The die member or plunger 10 is then moved down-

wardly toward the matrix. It will be noted that the upper end *e* of the ferrule *B* engages positively against the annular shoulder *10^x*, and that, as the plunger moves downwardly, the curved portion *10^y* thereof is forced into the upper end of the ferrule, thus expanding the same. As the member 10 continues to move toward the member 14 the metal forming the walls of the groove *b* collapses, as shown in Fig. 8, the metal being folded sharply back upon itself, as indicated at *b'*, and also at *c'*, thus forming an annular bead *c'* in place of the original shoulder *c*. It will be noted that this bead *c'* is of larger diameter than the original shoulder *c*, owing to the fact that the metal has been crowded outwardly by the die member and matrix. It will also be noted that the upper edge *e'* of the ferrule, as shown in Fig. 8, is of greater diameter than the edge *e* of the original ferrule. It will therefore be observed that the ferrule has been expanded both above and below the ring *C*, and this results in confining the ring between these expanded portions, and in causing the fabric to be securely gripped between the ferrule and the ring. Fig. 4, shows the ferrule as it appears after having been deformed in the manner just described, the fabric being omitted for the sake of clearness.

For carrying into effect the method above described I may conveniently employ the machine illustrated in Figs. 1 and 2. Referring to these figures it will be seen that the machine comprises a base 1 carrying a standard 2, which has a curved bifurcated upper end 3, between the forks of which is pivoted an operating lever 4, by means of a pin 5. The operating lever has a handle 6 and is also provided with a counterweight 4^a which is attached to the lever by means of a curved arm 4^b. This counterweight serves to return the lever automatically to the position shown in Fig. 1.

In the lower end of the lever 4 is formed a cam slot 7, in which works a roller (not shown) mounted on a pin 8, carried by the head 9 of a plunger or die member 10, which is slidably mounted for reciprocatory movement in a bracket 11, carried by the standard 2. The die member 14 having the matrix 13 at its upper end is mounted in a socket 15 carried by an arm 16 pivoted at 17 to the base 1. This arm 16 and die member 14 are capable of occupying either one of two positions. When in the position shown in the drawing, the outer end of the arm rests upon a seat 18, and when in its other position, such arm rests upon the seat 19, a stop 20 being arranged to limit the movement of the arm. In the center of each seat 18 and 19 is preferably arranged a spring pressed pin 21 having a rounded point which projects into a depression formed on

the lower side of the arm 16, and which serves to resiliently hold such arm in either one of its positions. A spring 22 secured to the base as by means of a screw 23 presses the pin 21 upwardly.

Immediately over the seat 19 is arranged a second plunger 24 which constitutes the stripping device now to be described. This plunger 24 has at its lower end a reduced portion or nose 25, which is of such size as to snugly fit within the smaller end of a ferrule *B*. The plunger is mounted for reciprocatory movement in a sleeve 26 which is secured to a bracket 27 carried by the standard 2. A laterally extending rod or handle 28 is secured to the upper part of the plunger 24 and projects through a slot 29 formed in the sleeve 26. The slot 29 is provided at each side with lateral offsets or notches 30 and 31 arranged at different heights, and into either of which the rod 28 is adapted to fit. A coil spring 32 lies within the sleeve 26 and surrounds the plunger 24 below the rod 28, so that it tends to force the plunger upward.

Considering Fig. 1, in connection with Figs. 5 to 8, previously described, the operation of the lever and plunger 10 in carrying out the deforming operation which results in attaching the ferrule to the umbrella case 95 will be readily understood.

After the deforming operation is complete, as shown in Fig. 8, it is then necessary to remove the umbrella case from the die and to turn it right side out. For this purpose the die member 14 is swung on its pivot until it rests upon the seat 19. The plunger 24 is then pressed downwardly by hand until the rod 28 reaches the level of the notch 31. The rod 28 is then swung laterally so as to engage the notch and lock the plunger in its lowermost position. This position is shown in Fig. 9, and by reference to this figure it will be seen that the reduced end 25 of the plunger extends through the ferrule while the body of the plunger engages the inner walls of the ferrule and holds it in position upon the die member 14. The lower end of the case may then be seized and pulled upwardly over the plunger 24, thus turning the same right side out as shown in Fig. 10. The rod 28 is then swung out of the notch 31 and released, whereupon the spring 32 forces it upward and disengages the plunger from the ferrule. The complete case, with the ferrule attached, may then be removed from the machine. Should it be desired to turn a finished case wrong side out again for any purpose, whatever, this may be done by first slipping the case over the die member 14 with the ferrule *B* projecting upwardly therefrom as shown in Fig. 2. The plunger 24 may now be moved downwardly until the shoulder at the lower end thereof engages the upper

end of the ferrule, and it may be locked in this position by swinging the rod 28 into engagement with the notch 30. The lower end of the case A may then be pulled up-
wardly around the plunger 24 thus turning the case inside out, whereupon the plunger may be released, as before, and the case removed. It will therefore be observed that by the use of my improved stripping device
10 the finished cases may be quickly reversed and turned either way at will. By so arranging the stripping device that the forming die may be swung into co-operative relation therewith, much time in the manipulation of the cases is saved and rapid opera-
15 tion results.

It will thus be seen that I have provided an improved method and machine by means of which tubular fabrics such as umbrella cases may be quickly and securely attached to ferrules, and it is thought that the many advantages of my invention will be readily appreciated by those skilled in the art.

What I claim is:—

25 1. The method of attaching a fabric to a ferrule having an exterior annular groove spaced from its ends and shoulders at the margins of the groove, which comprises arranging a closed ring around the attaching

portion of the fabric, passing the ferrule 30 into the portion of the fabric inclosed by the ring until the ring lies substantially in the plane of said groove, and then expanding one of said shoulders and collapsing the walls of the groove by axial compression of 35 the ferrule.

2. The method of attaching a fabric to a ferrule having an exterior annular groove and shoulders of unequal diameters at the margins of said groove, spaced from the 40 ends of the ferrule, which comprises arranging a closed ring, having an internal diameter intermediate the diameters of said shoulders, around the attaching portion of the fabric, passing the ferrule into the portion of the fabric inclosed by the ring until the smaller shoulder has passed through the ring and the latter lies substantially in the plane of the groove, and then expanding the smaller shoulder and collapsing the walls 45 of the groove by axial compression of the ferrule.

In testimony whereof I affix my signature in presence of two witnesses.

WILLIAM C. O'BRIEN.
